UNITED STATES PATENT OFFICE.

LIONEL A. CARTER, OF ST. LOUIS, MISSOURI.

LATHE.

Application filed April 20, 1923. Serial No. 633,550.

To all whom it may concern:

Be it known that I, LIONEL A. CARTER, a subject of Great Britain, and a resident of the city of St. Louis and State of Missouri, have invented a new and useful Improvement in Lathes, of which the following is a specification.

This invention relates to lathes and particularly to the manner of securing the face 10 or chuck plate to the head-stock spindle.

The principal objects of the present invention are to provide for readily attaching and detaching the face plate, to avoid "cocking" of the threads, to prevent wobbling of the 15 face plate on the spindle, and to obtain other advantages hereinafter appearing. The invention consists in the construction and combinations of parts hereinafter described and claimed.

20 The accompanying drawing which forms part of this specification, is a longitudinal sectional view of a portion of a lathe head-stock provided with a spindle and face plate construction embodying my invention.

25 The accompanying drawing shows only the forward end portion of the head-stock 1 and spindle 2 of a lathe. This construction of head-stock is well-known and it is considered unnecessary to illustrate it in de-

30 tail. The forward end of the spindle 2 is journaled in a suitable bearing 3 provided therefor in the head-stock 1 and has a hardened forward end or nose portion that extends beyond the forward end of the head-

35 stock and forms a support or bearing for a face or chuck plate 4 which is secured thereon. As shown in the drawing, the nose or forward end portion of the spindle 2 is of reduced diameter and is threaded externally,

40 as at 5, for cooperation with a threaded portion of the central cylindrical bore in the face or chuck plate 4.

The cooperating threads on the spindle and face plate terminate short of the forward ends of these members; and the portions of the spindle and bore that are located between their threaded portions and their forward ends are of substantially the same diameter, whereby the forward end

50 portion of the spindle cooperates with the forward end portion of the bore in the face plate and forms a bearing surface for the forward end portion of the face plate. The rear end portion of the bore in the face plate

55 is of a diameter corresponding to the diameter of the body portion of the spindle which

cooperates therewith and thus forms a bearing surface for the rear end portion of the face plate; and the annular shoulder 6 formed by the said enlarged rear end portion of said face plate abuts against the shoulder formed by the reduced nose portion of the spindle and thus takes the end thrust of the face plate.

It is noted as a very important advantage 65 of my invention that the face plate may be very quickly and easily mounted on the spindle; for the reduced nose portion of the spindle facilitates piloting of the face plate on the spindle; and it also relieves the operator of the weight of the face plate when turning the same to catch the thread and thus prevents damage thereto. It is also noted that the construction provides hardened and accurately ground bearing surfaces 70 both in front and back of the threads, which surfaces have an accurate fit in the large and small diameters of the bore in the face plate and thus prevent wobbling thereof. It is also noted that this wobbling or vibrating 75 of the face plate from side to side is further prevented by the engagement of the shouldered portion of the bore in the face plate with the thrust shoulder on the spindle.

It is obvious that changes may be made 80 without departing from my invention and I do not wish to be limited to the precise construction shown and described.

What I claim is:

1. The combination with a rotary spindle 90 having an end portion of reduced diameter and provided with threads, of a member having a central bore which is threaded for cooperation with the threaded portion of said spindle, the cooperating threaded portions of said spindle and said bore terminating short of said end of said spindle and the corresponding end of said bore, respectively, and the portions of said spindle and said 95 bore located between their threaded portions and said ends thereof being of substantially the same diameter, the opposite end portion of said bore being of a diameter adapted to fit the larger diameter of said 100 spindle.

2. The combination with a rotary spindle 110 having an end portion of reduced diameter and provided with threads, of a member having a central bore which is threaded for cooperation with the threaded portion of said spindle, the cooperating threaded por-

tions of said spindle and said bore terminating short of said end of said spindle and the corresponding end of said bore, respectively, and the portions of said spindle and said bore located between their threaded portions and said ends thereof being of substantially the same diameter, the opposite end portion of said bore being of a diameter adapted to fit the larger diameter of said spindle, the shoulder formed by the larger diameter of the bore in said member being adapted to abut against the shoulder formed by the reduced end portion of said spindle.

3. The combination with a head-stock of a lathe, of a spindle journaled in said head-stock with its forward end portion extending beyond the forward end of said head-stock, and a face plate adapted to be mounted on the forward end portion of said spindle, the forward end portion of said spindle being of reduced diameter and provided with threads, and said face plate being provided with a central bore which is threaded for cooperation with the threaded portion of said spindle the cooperating threaded portions of said spindle and said bore terminating short of their forward ends, and the portions of said spindle and said bore located between their threaded portions and their forward ends being of substantially

the same diameter, the rear end portion of said bore being of a diameter adapted to fit the larger diameter of said spindle.

4. The combination with a head-stock of a lathe, of a spindle journaled in said head-stock with its forward end portion extending beyond the forward end of said head-stock, and a face plate adapted to be mounted on the forward end portion of said spindle, the forward end portion of said spindle being of reduced diameter and provided with threads, and said face plate being provided with a central bore which is threaded for cooperation with the threaded portion of said spindle the cooperating threaded portions of said spindle and said bore terminating short of their forward ends, and the portions of said spindle and said bore located between their threaded portions and their forward ends being of substantially the same diameter, the rear end portion of said bore being of a diameter adapted to fit the larger diameter of said spindle, the shoulder formed by the larger diameter of the bore in said face plate being adapted to abut against the shoulder formed by the reduced forward end portion in said spindle.

Signed at St. Louis, Missouri, this 18th day of April, 1923.

LIONEL A. CARTER.
